Inventor:
Robert S. Valiant,

By Attorney D. G. Stickney,

UNITED STATES PATENT OFFICE.

ROBERT S. VALIANT, OF BALTIMORE, MARYLAND, ASSIGNOR TO UNDERWOOD TYPE-WRITER COMPANY, OF NEW YORK, N. Y., A CORPORATION OF NEW JERSEY.

TYPE-WRITING MACHINE.

949,720.

Specification of Letters Patent. Patented Feb. 15, 1910.

Application filed June 12, 1908. Serial No. 438,016.

To all whom it may concern:

Be it known that I, ROBERT S. VALIANT, a citizen of the United States, residing in Baltimore, in the State of Maryland, have 5 invented certain new and useful Improvements in Type-Writing Machines, of which the following is a specification.

This invention relates to paper manipulating devices of typewriting machines, and 10 particularly to means for gaging the sheet in the operation known as "retail billing and charging", and is an improvement on the device disclosed in Patent 829,989, granted September 4, 1906, to H. S. McCormack. 15 In said patent a plate having ledges is mounted on the delivery side of the platen, and the sheets are brought to register with the ledges or gages on said plate, by pressing the fingers on the surface of the sheet 20 and pushing it forward and sidewise to the gages. While the adjusting of the sheet once is but a small matter, still where the same sheet is inserted and adjusted and removed from the machine a great many times, 25 the repeated rubbing of the fingers thereon is apt to soil the sheet in some cases.

It is the object of the invention to improve said device, with a view to avoid the necessity of pressing the fingers forcibly upon 30 the sheet; and for this purpose I provide a recess in the rear edge of the plate, so as to permit the leading edge of the sheet to be readily picked up between the finger and thumb and pulled or set to the gages, with- 35 out any liability of soiling the sheet.

In the accompanying drawings, Figure 1 is a perspective view of a platen and platen frame of an Underwood typewriting machine with my improvement applied thereto. Fig. 2 is a sectional end elevation illustrating the manner of setting the sheet to the gages.

Type-bars 1 strike on the front of a platen 2, mounted by means of an axle 3 in the ends 45 4, 5, of a platen frame, which also comprises a paper table 6 in the rear of the

platen, provided with means 7 extending down around and up in front of the platen to guide the paper forwardly to the printing line. An adjustable gage 8 is usually 50 mounted upon the paper table 6 at the introductory side of the platen for the right hand edge of the sheet. Over the platen is mounted a plate or tablet 9 provided with ledges or gages 10, 10^a for the leading and 55 side edges of the sheet. The plate is adjustably supported by a pair of arms 11 secured to yokes 12 journaled upon a rod 13 secured in the platen frame, said yokes being locked on the rod against accidental rotation by means of spring-pressed rollers 14 engaging a groove 15 extending along the rod. I provide a recess 16 in the rear edge of said plate, about midway of its length, to permit the operator to conveniently pick up 60 the leading end of a sheet lying on the plate, to pull it forward and sidewise to the ledges or gages on said plate, without pressing or pinching the sheet so forcibly as to mark or smudge the same. 70

In operation, the feed rolls 17, 18 are cast off from the platen 2 in the usual manner. The sheet 19 is then inserted and slipped around the platen and onto the plate 9. The leading edge of the sheet is then picked 75 up by the finger and thumb and pulled forward and sidewise to square it with the ledges 10 and 10^a. The feed rolls are then thrown into engagement with the platen, and the writing proceeds. 80

Having thus described my invention, I claim:

In a typewriting machine, the combination with a platen and a platen frame, of a gage-plate lying along the top of the platen 85 and having a finger-recess to permit grasping the paper at the leading end to square it against the gage.

R. S. VALIANT.
